UNITED STATES PATENT OFFICE.

HARRY E. BEACH, OF NEWARK, NEW JERSEY, ASSIGNOR, BY MESNE ASSIGNMENTS, TO G. HOWLETT DAVIS, OF LLEWELLYN PARK, WEST ORANGE, NEW JERSEY.

ELECTRICAL SELF-PLAYING MUSICAL INSTRUMENT.

SPECIFICATION forming part of Letters Patent No. 709,295, dated September 16, 1902.

Application filed September 3, 1901. Serial No. 74,053. (No model.)

To all whom it may concern:

Be it known that I, HARRY E. BEACH, a citizen of the United States, and a resident of Newark, State of New Jersey, have invented 5 certain new and useful Improvements in Electrical Self-Playing Musical Instruments, of which the following is a specification.

My invention relates to self-playing musical instruments of the class wherein the 10 playing devices are actuated by means of a friction-shoe brought into engagement with a revolving roller or drum by the action of an electromagnet.

My invention is designed more particularly 15 for use with self-playing attachments for pianos, wherein a pivoted shoe is connected with or carries a striker-rod which actuates the striker or hammer of the piano in the usual way. A form of an electric self-playing 20 piano mechanism operating upon this general plan is described in the patent to G. H. Davis, No. 546,582. In apparatus of this character it is desirable to provide not only for an adjustment of the angle-bar or transverse rod 25 which carries the bank of magnets and friction-shoes to permit them to be adjusted as a whole to and from the actuating roller or drum, but it is also desirable to provide for the adjustment of the friction-shoes individ- 30 ually to provide for differences of individual wear or for other purposes.

The main purpose of my present invention is to provide a mechanism wherein both of these adjustments may be effected without 35 disturbing the adjustment of the armature of the electromagnet with relation to its poles, or, in other words, without varying the air-gap, although the chief utility of my invention lies in the capacity for individual ad- 40 justment without disturbing the air-gap.

To these ends my invention consists, first, in connecting the armature and pivoted shoe by devices which are capable of extension or contraction to vary the distance of the shoe 45 from the actuating-drum and in attaching to the armature or to the connections a stop device which is capable of maintaining its set or adjusted position despite any adjustment of the extensible and contractible connection 50 between the armature and shoe.

My invention consists further, broadly, in

the combination, with the magnet, its armature, and friction-shoe actuated thereby, of suitable positive stop devices limiting the back stroke of the armature under the action 55 of the usual spring, but mounted or connected with the armature and magnet in such manner that they will move with the same when the bar or angle-piece carrying the bank of magnets is adjusted to simultaneously adjust the whole bank of friction-shoes to and from the actuating-roller.

My invention consists, further, in the special combinations of devices whereby the objects of my invention are effected, or as more 65 particularly hereinafter set forth and as specified in the claims.

The accompanying drawings show one of the forms of apparatus in which my invention may be embodied.

Figure 1 is a cross-section through the angle-bar or support which supports the gang of magnets for a self-playing piano and through the revolving actuating roller or drum and shows in side elevation one of said magnets, 70 together with the friction-shoe and striker-rod actuated thereby. Fig. 2 shows in section a detail of the construction. Fig. 3 is a front elevation showing two of the striker-rods and actuating mechanism at one end of the frame 75 in which they are mounted or supported.

2 indicates an electromagnet, preferably of the horseshoe form, supported on the bar 3, which extends across the face of the instrument and is adjustable up and down toward 85 the actuating-drum 4. The two cores of the electromagnet set directly upon the bar 3, which acts as a yoke therefor and which is preferably of the angle form, as shown, to afford at one side a support for the armature 90 of said electromagnet. The armature is preferably attached to spring 5, which is secured by a screw 6 to the bar 3, as clearly indicated, and which may, if desired, be adjustable up and down on said bar. The spring 5 95 acts as a retractor-spring to retract the armature from the pole of the magnet after each operation in playing a note.

8 indicates the friction-shoe, which carries the striker-rod 9 in the usual or any proper 100 manner. This friction-shoe is connected with the armature 4, preferably by the rod 10, and

is pivoted upon a head or block 11, capable of adjustment upon the rod 10, to vary the distance of the shoe from the roller 1. Each shoe of the gang or range of shoes employed 5 in the attachment is similarly supported or connected with the armature to afford an extensible and contractible connection and permit the adjustment described. Also attached to the rod 10, but independently of the block 10 or head 11, is a collar or stop 14, which by engagement with the bar 3 or other part carried thereby limits the backward throw of the armature 4 and determines the width of the air-gap. The collar or stop 14 is preferably 15 also made adjustable upon the rod 10 to permit the extent of the air-gap to be nicely regulated or adjusted, which, as will be seen, can be accomplished without disturbing the adjustment of the connection 11 between the 20 armature and shoe. Also, as will be evident, after the adjustment of the air-gap by the stop 14 the connection of the shoe with the armature may be adjusted without disturbing the adjustment of the air-gap.

25 When it is desired to adjust the whole range of magnets and friction-shoes with relation to the drum, this can be effected by moving the bar 3 on its support and without in any manner disturbing the adjustment of the stop 30 that determines the width of the air-gap and without disturbing in any manner the individual adjustments of the springs for the several friction-shoes in the whole gang or range carried by the bar 3.

35 I do not limit myself to the special construction of the devices for permitting an adjustment of the connection between the armature and the shoe independently of the stop nor to the special construction of the 40 stop device for the armature. It will also be obvious that my invention is not limited to any particular construction of magnet or manner of supporting the same nor to the form of bar 3 or manner of adjusting it to adjust the 45 whole range of friction-shoes. Also the connection of the friction-shoe with the striker-rod or the manner of operating the same from the shoe form no part of my present invention, which is applicable not only to self-playing pianos, but to other musical instruments.

What I claim as my invention is—

1. In a self-playing musical instrument, the combination substantially as described,

of a friction-shoe and actuating-drum and an 55 electromagnet, of an extensible connection connecting the armature of the electromagnet and friction-shoe, and an adjustable stop device also carried by the armature and capable of adjustment independently of the adjustable connection between the armature and shoe.

2. In a self-playing attachment for musical instruments, the combination substantially as described of a friction-drum, a friction- 65 shoe, an electromagnet, an armature connected with said shoe, a support for the armature and magnet adjustable toward and from the drum, and stop devices for the armature whereby the air-gap may be limited, said stop 70 devices being carried by the armature and magnet support and both movable therewith when said support is adjusted to and from the drum.

3. In a self-playing attachment for musical 75 instruments, the combination with a bank of magnets, armatures and spring-retracted friction-shoes, of adjustable stop devices for each armature of the bank, an adjustable bar or angle-piece supporting all of said parts, re- 80 tracting-springs for said armatures wholly supported by said bar, and an actuating roller or drum with reference to which said bar or angle-piece is adjustable.

4. The combination in a self-playing mu- 85 sical instrument, of the bar 3 carrying the gang of magnets, an armature, an armature-rod 10 connected to said armature, a pivoted friction-shoe adjustably supported upon the rod, an adjustable collar 14 upon said rod and 90 an operating roller or drum 4, as and for the purpose described.

5. In a self-playing musical instrument, the combination of an electromagnet, an actuating-drum, a pivoted shoe, an armature, a stop 95 device adapted to limit the movement of the parts on the back stroke of the armature to limit the width of the air-gap, and an adjustable connection between the armature and shoe adjustable independently of said stop 100 devices, as and for the purpose described.

Signed at Orange, in the county of Essex and State of New Jersey, this 29th day of August, A. D. 1901.

HARRY E. BEACH.
